KEY-RESPONSIVE RECORDING CALCULATOR

James L. Hutton, Greensboro, N. C.

Application December 19, 1949, Serial No. 133,919

7 Claims. (Cl. 235—59)

1

This invention relates to improvements in computing machines and generally relates to improvements in computing machines, the subject of my pending applications Serial No. 731,799 and Serial No. 82,161 (now abandoned). A primary object of this invention is to complete or carry out the various functions with a more simplified and improved mechanism incorporating novel features and also providing a more economical machine from the manufacturing viewpoint.

A further object of this improvement is to provide a computing machine which involves a carrying or transferring mechanism actuated directly by the same mechanism which transfers the digits from the keyboard to the accumulating dials.

Another object of this improvement is to provide a printing mechanism for a computing machine which will enable a predetermined figure or amount to be printed through the use of a pre-set, selective, printing segment for printing true digits.

Still a further object of this improvement is to provide a carrying device so designed as to permit a carry or series of carries to be accomplished during the time that the keyboard energized selectors are rotating the accumulating dials, either in a positive or negative operation.

For a more complete understanding of the invention, reference is made to the accompanying drawings and specification, wherein like reference characters denote like parts.

In the drawings:

Figure 1 is a sectional side elevation view generally taken between the units and tens column of a mechanism showing the selection and carry parts with their essential associated members.

Figure 2 is a side elevation of some of the parts shown in Figure 1 to disclose more clearly the selector assembly.

Figure 3 is a partial, enlarged view of the mechanism shown in Figure 1, taken along line 3—3, looking in the direction of the arrows.

Figures 1, 2 and 3 disclose the essential working section of a computing machine constructed in accordance with the invention. Through this construction, addition and subtraction both are performed directly from the true key numerals without the use of complements, and carries, either positive or negative, are accomplished simultaneously with the movement of the selection, registering and recording members.

The mechanism illustrated permits the printing of the individual amounts set up on the keyboard without requiring any special timing or

2

holding bails at the time the carries are made, because the carry movements have absolutely no effect on the printing setting levers. In other words, the printing segments are set by trigger bars which are controlled directly by the keys of the keyboard. The selection parts receive their actions and movements by tripping said trigger bars but, on the other hand, the trigger bars are never affected by the selection parts once the differential position of said bar has been set by a depressed key, regardless of the carries that take place during the transaction.

The size of the keyboard, or the distance between the keys of the keyboard is not limited to the size of the gear pitch of the selectors, thereby allowing reduction in size of the selection parts and increase in size of the keyboard, which is a great advantage in arriving at a more desirable and balanced design for the machine.

Another feature of this construction is that the depression of any key or keys directly causes all of the selection parts and the carry parts to perform and complete their movements without the aid of any other actuating members. Therefore, the restoring bail of this mechanism has the purpose of merely restoring the selection parts and actuating the printing device.

As shown in the drawings, this latter improved construction is easily adapted to an electrically energized keyboard which permits the operation of this machine in a manner similar to other key-driven machines known in the art but, as compared to other present day machines this construction is greatly simplified, and requires a considerably smaller number of parts to perform and attain the same results and even offer greater features and advantages.

The keyboard shown in Figure 1 is basically the same as the one described and illustrated in my pending application Serial No. 731,799. It comprises a trigger type key assembly 310 working in relation with a trigger bar 312. A top plate 307, bottom plate 308 and two end bars 309 and 309a, form the supporting structure of the keyboard. The key assembly 310 (Figure 3) is composed of a main body stem 310a, a hook-like member 311 pivotally and slidably mounted on stem 310a through a shouldered rivet 313 fastened to stem 310a. A compression spring 314 coiled around stem 310a holds the key assembly in an upward position as shown in Figures 1 and 3 by exerting a pressure on shoulder 310b of the key stem and also on the lower edge 311a of the top section of hook member 311. Latching surface 311b of hook 311 lies at a point near a trigger bar 312,

in readiness for engagement with said bar, upon the depression of the key. At the start of the downward movement of the key stem, hook 311b is swung under trigger bar 312 through the action of cam surface 311c camming against the end of the slot in plate 308 through which member 311 slides. As hook 311b is cammed under bar 312, the bottom surface 310c of stem 310a comes in contact with the top edge of trigger bar 312 and exerts a downward push thereto. The downward travel of hook member 311 is halted by a shoulder 311e coming in contact with plate 308. When member 311 reaches its downward limit the key stem 310a is free to travel an additional amount, equal to the length of slot 311d the upper end of which abuts the rivet 313 during depression of the key assembly 310 by the trigger bar 312. Further manual depression of key stem 310a at this time causes cam tab 310d thereon to cam a slide 300 rearward on top of plate 307, a distance sufficient to cause a pair of electrical contact points 301 and 302 to make contact and thereby energize the working mechanism through driving means such as are disclosed in my pending application Serial No. 82,161. Each row of keys has its own contact making slide 300 and individual pair of contact points 301 and 302. However, all contact points of one pole could be integral parts of a single strip of electrical conducting material. At the time cam 310d contacts slide 300, all of the selection parts have completed their movement and are ready to be restored. Therefore, the closing of the electrical circuit at this time merely energizes the restoring mechanism.

The trigger bar 312 is pivotally mounted on shaft 322 and extends forward directly under the key stems as shown in Figures 1 and 3. The forward portion of said bar has a downwardly extending arm 312a, the purpose of which is to actuate the printing segment 303. The top edge 312b of bar 312 is straight and lies parallel with the ends of the key stem 310a. The lower edge 312c of said bar 312 is irregular and all the points of said edge, which lie in alignment with the hooks 311b, are calculated and located so as to allow a predetermined downward travel of bar 312 in relation to each individual key. That is, the number 4 key for example, will allow bar 312 to travel downward four times the distance that the number 1 key would allow. The number 7 key, seven times, etc.

Combination selector latching and trigger bar actuating member 331 is pivotally and slidably mounted through slot 331e on shaft 322, adjacent to bar 312, and extends forward. The forward end of latch member 331 terminates into a latching finger 331a forming a right angle with said member at a seat 320a formed at the bottom edge of a selector plate 320, and beyond which the bottom edge of plate 320 extends forwardly and downwardly to provide a cam surface 320b. At a point between finger 331a and shaft 322, the member 331 is slidably mounted through a slot 331b on a pin 312d which is securely fastened to arm 312. Directly below slot 331b is a downwardly extending leg 331c employed for restoring purposes. A portion of arm 31 extends to the rear of shaft 322 and terminates into a latching step 331d.

It can readily be seen that, whenever arm 312 is pushed downward, latch 331 will consequently be brought down with it through the action of pin 312d. As latch finger 331a leaves its seat 320a on selector plate 320, said latch will be cammed downward and follow cam surface 320b

until arm 312 comes to a stop according to whichever key was depressed. Released latch 331 is cammed downward by the rearward pull applied to selector plate 320 by spring 330. Selector plate 320 is slidably mounted on shafts 321 and 322 and allowed to slide rearward and forward through slots 320c and 320d with any rearward overtravel prevented by a restoring bail 334 which is disposed in the path of the downwardly extending selector plate surface 320b.

Two selection racks 315 and 316 are also slidably mounted on shafts 321 and 322, up against the side of selector plate 320 one on each side thereof. Both selector racks are identical but rack 316, which is mounted on the left side of selector plate 320, is in an inverted position in relation to rack 315. Two latches 318 and 319 are pivotally mounted on plate 320 at 318a and 319a. Latch 318 is on the left side of plate 320 and is in vertical alignment with the top edge of rack 316. Latch 319 is similar to latch 318 but is mounted in an inverted position in relation to latch 318 on the right hand side of plate 320, and in vertical alignment with the lower edge of rack 315.

The rear supporting rod 317 for racks 315 and 316 is part of a movable control bail 332 to which may be imparted up and down movement for the purpose of raising and lowering said racks simultaneously, into or out of mesh with dial 323. Rod 317 has two positions only. The lowered position, as shown in Figures 1 and 2 for addition, and the raised position for subtraction.

Each rack has a latch engaging notch 315a and 316a. When bail rod 317 is lowered, latch 319 becomes engaged with notch 315a in selector rack 315. When rod 317 is raised latch 318 then becomes engaged with selector 316. It can be seen that through this arrangement one selector or the other has to be in engagement with its related latch. Each latch has a spring 318b and 319b forcing said latches toward each other, their movement being limited by two stop pins 318c and 319c. The notch engaging points of latches 318 and 319 are far enough apart to allow only one of the racks to be engaged with its respective latch, but on the other hand, said points are close enough to each other to prevent both racks from being disengaged at the same time. Both racks are slideable rearward and forward but, through the above latch arrangement, only one rack at a time can ever be imparted movement. In other words both racks are slideable rearwardly but they will never slide simultaneously. Whichever rack is out of engagement with its latch is always held in its home position by its relative spring 335 for rack 316 and spring 337 for rack 315. One end of each spring is hooked to a tab extending from the edge of the selector rack and the other end hooked to the stationary shaft 321.

By the above description it can readily be seen that, whenever plate 320 is released through the depression of a key and bar 312, said plate 320 will travel rearward and bring with it rack 315 since the latter is engaged with latch 319. The amount of rearward travel of plate 320 is controlled and predetermined by the depression of a chosen key on the keyboard. For instance, by depressing the number 3 key on the keyboard, plate 320 is released and allowed to travel rearward a distance equal to three spaces or teeth on rack 315. The downward movement of latch 331 is limited through the action of bar 312 and 75 the key depressed. The angle of cam surface

320b is figured and positioned so as to work in relation with and in proportion to the downward movement of latch finger **331a**. Latch **331a** swings in an arc from shaft **322** and is free to swing downward nine equal spaces or steps in addition to the initial unlatching step. Trigger bar **312** serves a double purpose. First, it serves as a trigger to release latch finger **331a** from its seat **320a** on selector plate **320** and second, it serves as a limit or a stop for latch **331a** at the time it (bar **312**) reaches its lowest travelling point in engagement with the hook **311b** of a depressed key. Since bar **312** swings in a downward arc around shaft **322**, and since the keys working on said bar lie at different intervals from shaft **322** in relation to said bar it is hereby evident that a compensation has to be made to overcome the different distances existing between shaft **322** and every one of the keys. This connection or compensation is acquired through the irregularity of the lower edge of bar **312** in relation to the hooks **311b** of the keys. Whenever a key is depressed, a portion of the downward travel of the key and more specifically the first portion thereof is utilized for placing hook **311b** underneath bar **312** and for bringing latch **331a** out of its latched position. After latch **331a** moves out of its seat **320a**, spring **330** pulls selector plate **320** rearward thereby causing said latch **331a** to be cammed downward along cam surface **320b** until bar **312** reaches its downward limit which is governed by the depressed key. Notice should be taken at this time that after releasing latch **331**, the movement of bar **312**, latch **331**, selector plate **320**, rack **315** and dial **328** is entirely dependent upon the rearward pull of spring **330**.

The length and angle of cam surface **320b** is calculated in accordance with the total rearward travel of plate **320** and the total length of the downward stroke of bar **312** and latch **331**. Plate **320** and bar **312** both have nine different stopping positions, one for every key. Every stopping place represents one tooth or space on racks **315** and **316**. Since hook **311b** and bar **312** become engaged, the downward travel of said bar **312** is halted whenever shoulder **311e** (Figure 3) strikes plate **308** of the keyboard.

The downward extending arm **312a** of bar **312** terminates in a camming surface **312e** which acts upon and causes rotating movement to printing segment **303** by contacting a cam pin **303a**. The gap between cam surface **312e** and cam pin **303a** represents the amount of downward travel of bar **312** required to unlatch member **331** from its seat.

The movement of segment **303**, therefore, is not affected until the time when the selection parts begin their differential displacement. The locations of cam surface **312e** and pin **303a** are calculated, in relation to their arcs of movement, to differentially adjust the printing segment **303** in correspondence with the differential displacement of bar **312** and plate **320**. The printing device disclosed in Figure 1 is operated and controlled in a manner similar to my printing device described in my above noted pending applications Serial No. 731,799 and Serial No. 82,161. In Figure 1 portions of the type aligner **258** and firing platen **256** are shown as a matter of reference.

To accomplish an addition problem, for example $55+88$, the amount **55** is entered in the keyboard by depressing the number **5** key in both the units column and the tens column. Both

5 digits of the amounts **55** may be entered simultaneously, or separately and/or from left to right or right to left. The same situation exists at the time of entering the next amount which is **88**.

10 As explained above, selector plate **320** starts its rearward pull immediately upon releasing latch **331** through the depression of a key. Bail **332** is down (for addition) and latch **319** is engaged with rack **315**. It can readily be seen, that since latch **319** is fastened to plate **320**, rack **315** will consequently move rearward along with said plate **320** through the action of said latch. The rack **315** in both the units and tens column will advance rearward five teeth, thereby, rotating their related dials an equal number of teeth to register the amount **55** in said dials. Rack **316** is held in its normal or home position by spring **335** during the rearward travel of plate **320** and rack **315**.

15 At the time the selection parts come to a stop the shoulders **311e** of the depressed keys are down against plate **308**. The next operation is to depress one of the key stems an additional amount through slot **311d** which will cause cam slide **300** to be cammed rearward and close contact points **301** and **302** thereby energizing the restoring controls.

20 Normally restoring bail **334** stands at a rearward distance from arm **331c** and heel **320b** greater than the total rearward travel of heel **320b**. This allows a small amount of free forward travel of bail **334** at the start of its forward travel. During said small amount of free travel means are provided to cam bail **332** upward thereby throwing rack **315** out of mesh with dial **328**. By doing so rack **316** will consequently move up into mesh with dial **328** to serve as a retainer and prevent any movement of the dials. 25 During the restoring of the selection parts. At the end of the restoring operation, bail **332** is again reset to its lowered position as shown in Figures 1 and 2. The raising and lowering of bail **322** can be accomplished in the manner shown in my above noted pending applications in regards to reversing controls for addition and subtraction. As the selection parts are being restored and, more specifically, as bar **312** moves upward through spring **388** the key assembly will be forced upward through spring **314**. Near the end of the upward movement of the key assembly the upper surface **311e** of hook member **311** will come in contact with top plate **307** and through the upward push of spring **314** said hook member **311** will be imparted a rotating movement around rivet **313** thereby causing hook **311b** to resume its normal position as shown in Figure 3.

30 The second amount of the problem which is **88** is now entered in the keyboard in the same manner as the first amount. The functions and movements of the selection parts in this case are the same as above. In addition to said functions and movements, it is evident that two carries will have to take place. One from the units to the tens column and one from the tens to the hundreds column.

35 The arrangement of the carry levers is such that every carry lever extends from its relative dial to the carrying device in the column to the left thereof when viewed from the top. As it appears in Figure 1, carry lever **326** is rotatably mounted on a rod **336** with its forward extending arm terminating in a latching finger **326a** forming a right angle therewith and engaging the latch member **331** of the tens order. For the

sake of clarity, the rear upwardly extending arm 326b of carry lever 326 has been omitted, since it does not come in contact with the tens dial carry finger 329 shown in Figure 1. However, a shadow outline of arm 326b has been illustrated to show its relative position in regards to carry finger 329 and the bail rod 244a.

Returning to the addition problem, it can be seen, that when the two dials containing the amount 55 are rotated eight more teeth, their carry fingers 329 will come in contact with and cam the carry levers 326 out of engagement with the latch members 331 of higher order. As previously explained latch member 331 is free to move longitudinally through its slots 331b and 331c a distance equal to one tooth on one of the selector gear racks. It is hereby evident that whenever carry lever 326 is tripped out of engagement with latch member 331 the latter will be advanced to its rearward limit through the action of selector plate 320 and spring 330. (The same action takes place whenever a tens transfer occurs with or without digitation of selector plate 320 and rack 315.) In this problem the carry takes place at the very moment that the units dial is rotated five of the eight places that it has to rotate. In other words, the differential displacement of the selection mechanism as controlled by the keyboard and the added increment imparted by a tens carry are accumulated simultaneously as a single movement.

The extra rearward movement of plate 320 and latch 331 in the event of a carry has absolutely no effect on the downward movement of trigger bar 312, therefore, it is evident that nothing but the true keyboard amount will ever be transferred to the printing segments regardless of any carry or carries taking place. This construction consequently eliminates the necessity of the conventional timing and holding means to prevent carries from taking place prior to the printing operation.

The above mechanism works generally the same for subtraction, with the exception that in this case, bail 332 is normally held in a raised position, rather than a lowered position as previously described, through any well known control lever arrangement which is set prior to a subtraction operation.

Although the foregoing discloses the invention it is not intended for said invention to be limited to the above description and accompanying drawings as this device covers a wide scope and a study thereof will reveal an unlimited range of modifications and improvements which are apparent.

I claim as my invention:

1. In a calculating machine having a keyboard and an accumulator, differential actuators controlled by said keyboard and biased for movement from a normal home position to actuate said accumulator, latching means normally holding each of said actuators at said home position, said latching means being settable by an operated key of said keyboard to release the corresponding actuator from said home position and to intercept said actuator at a position corresponding to the value of the operated key, and tens transfer means operated by an adjacent order of said accumulator to release said latching means and corresponding actuator for limited supplemental actuating movement from said home position to register a tens transfer in said accumulator at the order of said operated key either before or after operation of said key.

5 2. In a calculating machine having a keyboard and an accumulator, differential actuators controlled by said keyboard and biased for movement from a normal latched position to actuate said accumulator, latching means for each of said actuators normally holding said actuators at said latched position, each of said latching means being settable by an operated key of the corresponding order in said keyboard to release said corresponding actuator from said latched position and to intercept said actuator at a position corresponding to the value of the operated key, and tens transfer means operated by an adjacent order of said accumulator to release said latching means with the corresponding actuator for limited supplemental actuating movement from either said latched position or said intercepted position to register a tens transfer in said accumulator at the order of said operated key either before or after operation of said key.

10 3. In a calculating machine having a keyboard and an accumulator, differential actuators controlled by said keyboard and biased for movement from a normal latched position to actuate said accumulator, a pivoted trigger bar for each of said actuators, latching means for each of said actuators carried by said trigger bars for pivoting movement therewith and for limited 15 sliding movement independently thereof in the direction in which said actuators are biased, each of said actuators being formed with a latching seat and with an adjacent cam surface, each of said latching means normally engaging said 20 actuators at said latching seat and thereby holding said actuators at said latched position, each of said trigger bars being pivotable by an operated key of the corresponding order in said keyboard to release the latching means for the corresponding actuator and thereby allow movement of said actuator from said latched position, said trigger bars also being settable by said operated key for disposing the released latching means for abutment by the cam surface of said actuator at a position intercepting said actuator after movement corresponding to the value of said operated key, and tens transfer means operated by an adjacent order of said accumulator to release said latching means independently for said limited sliding movement with said actuator to register a tens transfer in said accumulator at the order of said operated key.

25 4. In a calculating machine having a keyboard and an accumulator, the structure defined in claim 3 and further characterized in that a printing segment is pivoted adjacent each of said trigger bars with a printing face formed thereon concentrically with the segment axis, said printing segments being pivotally settable by said trigger bars in relation to the key operated pivoted setting of said bars for thereby disposing the printing faces of said segments to print a value corresponding to an operated key.

30 5. In a calculating machine having a keyboard and an accumulator, the structure defined in claim 3 and further characterized in that a pair of oppositely disposed rack elements is slidably assembled with each of said actuators and independently biased for retention at said latched position, shifting means is provided for selectively engaging one of said rack elements with said accumulator, and means is carried by said actuators for latching the accumulator engaged rack element for actuating movement therewith, the other rack element being disposed to engage said

accumulator to hold a registered value therein upon disengagement of said first rack element for restoring said actuator to said latched position.

6. In a calculating machine having a keyboard and an accumulator, the structure defined in claim 3 and further characterized in that an order of keys is provided in said keyboard corresponding to each of said trigger bars, said keys each comprising a stem disposed to bear on the corresponding trigger bar for pivoting the same upon operation and an opposed hook element disposed oppositely with respect to said trigger bars for limiting the pivoting movement thereof in correspondence with the value of an operated key, and said keys each being biased toward a normal non-operated position, the bias of said keys serving to cushion the interception of said actuators.

7. In a calculating machine having a keyboard and an accumulator, the structure defined in claim 3 and further characterized in that said machine also includes means for restoring a released actuator to said latched position, a pair of normally open electrical contacts for controlling operation of said restoring means, an order of keys in said keyboard corresponding to each of said trigger bars with each key comprising a stem disposed to pivot the corresponding trigger bar and thereby release the corresponding actuator upon initial operation of the key, a slide for each order of said keys in said keyboard, each

slide being arranged in relation to the stems of all the keys in the corresponding order and being disposed for sliding movement in relation to said pair of electrical contacts between a normally maintained position corresponding to the normally open condition of said contacts and a displaced position at which said slide causes said contacts to close, and each key stem being formed with a cam tab disposed to engage the corresponding slide and cause sliding movement thereof to said displaced position upon further operation of an initially operated key.
